UNITED STATES PATENT OFFICE.

JOHN A. SONS, OF HUMBLE, TEXAS, ASSIGNOR OF ONE-HALF TO ROBERT M. LAYTON,
OF HARRIS COUNTY, TEXAS.

PUMP PRESSURE GOVERNOR.

Application filed June 22, 1925. Serial No. 38,668.

To all whom it may concern:

Be it known that I, JOHN A. SONS, a citizen of the United States residing at Humble, in the county of Harris and State of Texas, 5 have invented certain new and useful Improvements in a Pump Pressure Governor, of which the following is a specification.

This invention relates to new and useful improvements in a pressure pump governor.

One object of this invention is to produce a governor, adapted to be actuated by the pressure of fluid being pumped, and which in turn governs the operation of the pump so as to maintain a substantially uniform 15 pressure and consequently a uniform discharge from the pump.

Another object of the invention is to provide a governor of the character described which may be adjusted, or regulated, so as 20 to readily vary the capacity of the pump.

With the above and other objects in view this invention has particular relation to certain novel features of construction, operation and arrangement of parts, an example 25 of which is given in this specification and illustrated in the accompanying drawings, wherein:—

Figure 1 shows a side elevation of a pump operatively connected with a motor and 30 equipped with the type of governor, herein described.

Figure 2 shows a longitudinal sectional view of the governor and

Figure 3 shows a plan view thereof. 35 Referring now more particularly to the drawings, wherein like numerals of reference designate similar parts in each of the figures, the numeral 1 designates a slush pump having a suction line 2 and a discharge 40 line 3.

The pump is driven in the usual way from the motor 4 through the drive belt 5. The motor shown is equipped with the usual throttle for controlling the feed of the motive fluid thereto, said throttle having the usual throttle valve arm 6 through which the conventional throttle valve may be operated.

The governor includes a cylinder 7, one 50 end of which is connected into the discharge line 3 through the reduced nipple 8. The other end of the cylinder has the plug 9 screwed therein. Within the cylinder there is a floating plunger 10 with the oil chamber 11 between it at the end plug. This

chamber is normally filled, with oil which may be introduced through the inlet pipe 12 which is normally closed by the plug 13. Interposed between the plunger and the plug 9 there is a strong coil spring 14 and 60 a pressure gauge 15, of conventional construction, is connected into the chamber 11.

The upper end of the cylinder carries a bracket 16 fulcrumed on which there is a bell crank lever 17, one arm of which is 65 connected with the throttle valve arm 6, through the rigid rod 18.

Fulcrumed on the free end of the other arm of the lever 17 there is an adjusting lever 18, and the adjusting bolt 19 fits loosely through one end of the adjusting lever with its lower end enlarged and resting on the lever 17 and its upper end threaded to receive the nut 20. A coil spring 19' surrounds the bolt 19 and is interposed between 70 the enlarged lower end thereof and the adjacent end of the lever 18. The other end of the lever 18 rests on the reduced upper end 21 of the plunger 22 which works in a cylindrical axial bearing through the plug 9. 80

Pressure in the line will operate through the nipple 8 and against the plunger 10 and when a predetermined pressure is exceeded the fluid in the chamber 11 will operate through the plunger 22 to actuate the levers 85 18 and 17, and through the rod 18 will influence the throttle valve and thereby reduce the engine speed which will in turn reduce the pump pressure. Thereupon the plunger 10, acting under the influence of the 90 spring 14, will move back and the partial vacuum created in the chamber 11 will cause the normal air pressure to release the pressure of the plunger 22 against the lever 18, and the throttle will be again opened through 95 the pull of the spring 23.

The pressure required to operate the governor may be varied by adjusting the plug 9 so as to vary the capacity of the chamber 11, and the range of influence of the governor on the throttle may be varied by adjusting the spring 19'. 100

What I claim is:—

1. A governor including a cylinder one end of which is adapted to be connected into a fluid pressure line, a pair of plungers therein spaced apart to form a fluid chamber between them, an actuating lever fulcrumed on the other end of said cylinder, one of said plungers being disposed to be 105 110

operated by pressure from said line and the other being disposed to actuate said lever.

5. 2. A governor including a cylinder, an actuating lever associated with the cylinder at one end, a plunger mounted in the cylinder and adapted to actuate said lever, a movable septum in the cylinder forming a fluid chamber between it and said plunger, a pressure fluid inlet connected into the other 10 end of the cylinder.

15. 3. A governor including a cylinder, an actuating lever associated with the cylinder at one end, a plunger mounted in the cylinder and adapted to actuate said lever, a floating plunger in the cylinder forming a fluid chamber between said plungers, a pressure fluid inlet connected into the other end 20 of the cylinder and a yieldable seat in said chamber against which the floating plunger is seated.

25. 4. A governor including a cylinder, a pivotally mounted actuating lever associated therewith, a plunger in the cylinder adapted to actuate said lever, a pressure fluid inlet entering the cylinder, a movable septum in the cylinder and which is spaced from the plunger and which is arranged between it and said inlet, thus forming a chamber between said septum and plunger.

30. 5. 5. A governor including a cylinder, a pivotally mounted actuating lever associated therewith, a plunger in the cylinder adapted to actuate said lever, a pressure fluid inlet entering the cylinder, a floating plunger in

the cylinder forming a movable septum 35 which is spaced from the first named plunger and which is arranged between it and said inlet, thus forming a chamber between said plungers and a pressure gauge connected into said chamber.

40. 6. A governor including a cylinder, a pivotally mounted actuating lever associated therewith, a plunger in the cylinder adapted to actuate said lever, a pressure fluid inlet entering the cylinder, a floating plunger in the cylinder forming a movable septum 45 which is spaced from the first named plunger and which is arranged between it and said inlet, thus forming a chamber between said plungers and a yieldable seat between the 50 plungers against which the floating plunger is seated.

55. 7. A governor including a cylinder, a pivotally mounted actuating lever associated therewith, a plunger in the cylinder adapted to actuate said lever, a pressure fluid inlet entering the cylinder, a floating plunger in the cylinder, forming a movable septum which is spaced from the first named plunger and which is arranged between it and said 60 inlet, thus forming a chamber between said plungers, a pressure gauge connected into said chamber, and a yieldable seat in said chamber against which the floating plunger is seated.

65. In testimony whereof I have signed my name to this specification.

JOHN A. SONS.
